Primary Examiner — Kelley Donnelly(74) *Attorney, Agent, or Firm* — DuBois, Bryant & Campbell LLP; William D. Wiese(57) **CLAIM**

The design for a modular tray organizer, as shown and described.

DESCRIPTION

FIG. 1 is a perspective view of the modular tray organizer;
FIG. 2 is a top view thereof;
FIG. 3 is a back view thereof;
FIG. 4 is a longitudinal side view of the lower frame thereof;
FIG. 5 is a top isometric view of the bottom frame thereof;
FIG. 6 is a top view of the lower part of the structure for product transportation and protection;
FIG. 7 is a front view thereof;
FIG. 8 is a side view thereof;
FIG. 9 is a front top view of a second embodiment thereof;
FIG. 10 is a front top view of a third embodiment thereof;
FIG. 11 is a front top view of a fourth embodiment thereof; and,
FIG. 12 is a front top view of a fifth embodiment thereof.
